UNITED STATES PATENT OFFICE.

GEORGE F. GALE, OF WINTHROP, ASSIGNOR OF ONE-HALF TO ARNOLD B. HOLMES, OF BOSTON, MASSACHUSETTS.

ELECTRICAL CALL-BOX.

SPECIFICATION forming part of Letters Patent No. 431,141, dated July 1, 1890.

Application filed February 27, 1890. Serial No. 341,950. (No model.)

To all whom it may concern:

Be it known that I, GEORGE F. GALE, of Winthrop, in the county of Suffolk, State of Massachusetts, have invented certain new and useful Improvements in Electrical Call-Boxes, of which the following is a description sufficiently full, clear, and exact to enable any person skilled in the art or science to which said invention appertains to make and use the same, reference being had to the accompanying drawings, forming part of this specification, in which—

Figure 1 is a front elevation showing the escapement mechanism of my improved call-box. Fig. 2 is a side elevation of the same; Fig. 3, a front elevation of the box, the face being removed to show the interior mechanism; and Fig. 4 an edge elevation, partly in section, on line xx in Fig. 3.

Like letters and figures of reference indicate corresponding parts in the different figures of the drawings.

My invention relates especially to an improved escapement mechanism for electric messenger call-boxes; and it consists in certain novel features, hereinafter fully set forth and claimed, the object being to produce a simpler, cheaper, and more effective device of this character than is now in ordinary use.

The nature and operation of the improvement will be readily understood by all conversant with such matters from the following explanation.

In the drawings, A represents the back plate of the box, which is provided with flanges b, in which are formed screw-holes d for attaching it to the wall. Guards f prevent the plates from coming directly into contact with said wall. A V-shaped frame g is secured by screws h to the face of the plate A. A horizontal shaft i is journaled in the apex of said frame and plate. A crank-handle j is secured to the outer end of said shaft, said handle being disposed outside the case by which the mechanism shown is covered. A large gear B is secured on the shaft i, and a flat spring k is wound on said shaft between the gear and back plate, one end of said spring being secured to the shaft and the opposite end to said back plate. Said spring acts torsionally

to return the shaft after having been rotated by the crank. Series of openings l m p are formed in the body of the gear and openings corresponding in number with the number of the call-box. A post q passes through the back plate and is insulated therefrom by rubber disks r t. A nut and plate s v on said post at the rear of said back plate form a connector for a wire of the electric circuit, the opposite pole-wire being connected directly to the plate A. A vertical brush w is secured to the post q, said brush having two arms y z in engagement with the face of the gear B, the brush-arm z being disposed so that its free end will enter the openings l m p as the gear is rotated. A disk 15 of insulating material is disposed loosely on the shaft i between the frame g and gear B, and is provided with a radial arm 16 in position to pass under and disengage the brush-arm y from the face of the gear when the disk is rotated. The tension of the spring k forces a stop 17 on the gear against said disk-arm and tends to hold it out of contact with the brush-arm, a similar stop 18 on the arm 16 at the same time engaging a boss 19 on the frame g, and prevents the disk from being rotated too far by the spring. A vertical lever 20 is pivoted at 21 by its lower end to the plate A. A stop 22 on said plate restricts the movement of said lever in one direction. A laterally-projecting pin 23 is secured to said lever, and a loose pinion 24 is disposed thereon, said pinion meshing with the gear B. On the outer end of said pin a V-toothed ratchet 25 is mounted, a four-arm spring 26 on said pin bearing against the outer face of said ratchet. The tension of said spring is adjusted by means of a nut 27, turned onto the outer end of the pin.

A pawl D is pivoted to the back plate A in the same plane as the ratchet 25, and has a rectangular groove 28 in its edge forming two parallel teeth 29, adapted to engage the ratchet-teeth and restrain the movement of said ratchet. An adjusting-screw 30 passes through the free end of the lever 20 into engagement with the pivot of the pawl D, the purpose of said screw being to regulate the right-to-left movement of said lever.

In the use of my improvement, the crank

j being turned from left to right, the gear *B* is moved in a corresponding direction. Both arms of the brush *w* being in contact with the gear, a closed circuit is sustained. As the 5 last of the openings *p* passes under the brush-arm *z*, a stud 33 on the face of the gear engages the disk-arm 16 on the left, as viewed in Fig. 3, forcing said arm under the brush-arm *y* and disengaging it from contact with 10 the gear, the arm *z*, however, continuing in contact therewith. As soon as the crank is released the spring *k*, wound by the rotation of the shaft *i*, causes it to rotate in the opposite direction. The slots *p m l* passing 15 consecutively under the brush-arm *z*, each breaks the electric circuit and indicates thereby at the central office the number of the box in the usual manner. The arm 16 of the insulating-disk is stationary under the brush-arm until 20 the last opening *l* has passed the brush-arm *z*, when the stop 17 on the gear engages said insulator and moves it out of contact with said brush until its stop 18 meets the frame *g*, stopping the mechanism. A plate 35 on 25 the post *g*, bearing against the brush, regulates the pressure of its arm *z* on the gear, so that there shall be an absolute break of its contact with said gear when the openings *l* *m p* pass thereunder. The point of the brush-arm is V-shaped in side elevation (see Fig. 30 4) to better effect this. As the crank is operated to rotate the gear, as described, the lever 20 is carried thereby from left to right until it meets the stop 22. The tension-spring 35 26 jams the ratchet 25 sufficiently hard against the pinion 24 to prevent said pinion rotating and traveling on the gear until said lever on which the pinion is journaled meets the stop 22. Upon the return of the gear *B*, 40 by means of the spring *k*, the lever 20 is thrown back again from right to left, its screw 30 meeting the pawl-pivot and the ratchet 25 at the same time engaging the teeth of said pawl, which acts as a double-toothed click to retard 45 the motion of the gear-train. By thus pivoting the escapement mechanism so that the click and ratchet are out of contact during the winding of the spring one-half of the wear upon the ratchet-teeth is avoided. Moreover, 50 ratchets with teeth cut with far less accuracy may be employed than when the ordinary pawl is used, and much less care is necessary in the adjustment of the parts. The wear of the ratchet-teeth may be compensated for by 55 turning out the screw 30 and permitting the

gear to throw said ratchet so much nearer the click.

The construction of the device is greatly lessened in cost by the use of my improved escapement, the necessity of employing 60 spring-pawls and similar expensive parts being done away with.

Having thus explained my invention, what I claim is—

1. In an escapement mechanism, the combination of a double-toothed click pivoted to a fixed plate or support, a reciprocating main gear, a pivoted lever, a ratchet and pinion journaled on said lever, said pinion meshing with the gear and said ratchet being disposed 70 in position to engage the click when the gear reciprocates, substantially as set forth.

2. An escapement mechanism comprising the pivoted lever 20, bearing the pinion 24 and ratchet 25, said pinion meshing with a 75 reciprocating gear, stops for the lever, the tension-spring 26, and click *D*, combined substantially as described.

3. In an escapement mechanism, the reciprocating gear *B*, combined with the pivoted 80 lever 20, bearing a ratchet and pinion meshing with said gear, an adjustable stop carried by the lever, and a double-toothed click in position to engage said ratchet, substantially as described.

4. In a call-box, the combination of a back plate, a spring-reciprocated indicating-gear, a two-arm brush in contact therewith, an insulating-plate on the gear-shaft adapted to engage a brush-arm, stops on the gear and 90 plate for determining their rotation, and an escapement comprising a double-toothed click and a pinion and ratchet mounted on a pivoted support, said pinion meshing with the gear, substantially as and for the purpose set forth.

5. In a signal or call box, a reciprocating gear having indicating-slots in one-half or less of its surface, a two-arm contact-brush, one arm thereof being placed to enter said 100 slots and the companion arm normally in contact with the surface of the gear, and an insulating-plate on the gear-shaft for breaking the contact of said arm until the companion arm passes said slots, substantially 105 as described.

GEORGE F. GALE.
